C. L. RAYFIELD

ELECTRICAL IGNITION SYSTEM FOR OIL BURNERS

Filed May 6, 1926

UNITED STATES PATENT OFFICE.

CHARLES L. RAYFIELD, OF CHICAGO, ILLINOIS, ASSIGNOR TO RAYFIELD MANUFACTURING COMPANY, OF CHICAGO, ILLINOIS, A CORPORATION OF ILLINOIS.

ELECTRICAL IGNITION SYSTEM FOR OIL BURNERS.

Application filed May 6, 1926. Serial No. 107,034.

This invention relates to a method of and an apparatus for igniting oil burners and specifically comprises a pair of electrical conductors having approaching conical terminals located adjacent but preferably not directly in the path of the oil or fuel emerging from the nozzle, for the purpose of producing a spark for igniting the fuel.

The invention comprises the novel structure and combinations hereinafter described and more particularly pointed out and defined in the appended claims.

It is believed that applicant's novel method of igniting an oil burner will be fully understood by a description of the apparatus by which the method may be practised.

In the accompanying drawings which illustrate a preferred embodiment of this invention and in which similar reference numerals refer to similar features in the different views:

Figure 1 is an elevational view of a furnace partly broken away showing a portion of the oil burner in elevation;

Figure 2 is an enlarged sectional view through the nozzle of the burner showing the ignition wires in elevation;

Figure 3 is an enlarged sectional view through the oil burner showing one of the conductors of the ignition system with the nozzle and supply pipe in elevation.

Figure 4 is a sectional view upon the line IV-IV of Figure 3;

Figure 5 is a bottom plan view upon the line V-V of Figure 3.

In the drawings there is shown an oil burner comprising a spherical hood 1, to which a cylindrical sleeve or casing 2 is connected. The fuel nozzle 3 is supported obliquely in the hood 1. The nozzle 3 connects with an oil supply pipe 4, which extends through the sleeve 2. The fuel entering through the pipe 4 passes through an aperture 5 into a central chamber of the nozzle and emerges from the chamber 6 through the interstices of the atomizing heads 7 which are located adjacent the outlet of the nozzle. Air for carburation is ordinarily introduced through the sleeve or casing 2 by a blower or other well known means and mixes with the fuel discharged

from the nozzle to form a combustible mixture.

The particular structure of the burner forms no part of the present invention except in so far as it cooperates therewith. This invention concerns itself primarily with means for producing an electrical spark adjacent the outlet of the nozzle. To this end a pair of electrical conductors 8 are supported on the housing. The rear ends of these conductors are turned at right angles and rigidly attached to an insulated plate 9 which is attached to a cylindrical opening in the bottom of the sleeve 2. The attachments of the conductors to the plate 9 are preferably effected by means of inner and outer nuts 10 threaded upon the right angled portions of the conductors 8 whereby the conductors are adjustably mounted upon the plate 9 in order that their ends may be properly positioned with respect to the path of the fuel emerging from the nozzle. These conductors extend from the plate 9 in parallel relation to the dome or hood 1 of the burner where they are curved downwardly toward the exit of the nozzle. The ends 11 of the conductors 8 are deflected at an angle toward each other and are substantially of conical formation and they are so proportioned as to their length to provide a suitable gap 12 for the production of a spark for igniting the fuel mixture. Any suitable source of electrical energy may be connected with the conductors 8 by the supply wires 13 and 14 connected to the threaded portion of the conductors 8 by means of suitable nuts 15. It will, of course, be understood that proper transformers and high tension spark coils and suitable switches for the ignition circuit will be used in the supply circuit. They are not illustrated, as any standard construction will suffice.

It will be noted that the points of the electrodes 11 are slightly to the rear of the fuel discharge from the nozzle. This prevents fouling of the electrodes and at the same time, effective ignition is assured by the flow of air, (usually under pressure), through the sleeve 2 which blows the spark produced at said electrodes into the com-

bustible mixture formed by said air and the atomized fuel discharged from the nozzle.

I am aware that numerous details of construction may be varied through a wide range without departing from the principles of this invention, and I therefore do not purpose limiting the patent granted hereon, otherwise than necessitated by the prior art.

10. I claim as my invention:

1. In combination in an oil burner a tubular member comprising an air tube and having connected to it an angularly formed end provided with a discharge orifice, a fuel nozzle positioned in said end and a plurality of spark electrodes each comprising an angularly bent member including a leg disposed within the tubular member and connected thereto and a leg disposed in said end of the tube alongside of said nozzle and means for adjusting each of said electrodes in such a manner as to enable the end of the leg of each of them adjacent the nozzle to be at all times out of the path of the jet leaving the nozzle but sufficiently close thereto that the spark emanating from said electrodes will be blown by the air in said tube into said jet.

2. In combination in an oil burner, a tubular member comprising an air tube, a fuel nozzle in an end of said tube, spark emitting means positioned in said tube including spark electrodes each comprising an angularly bent rod including a leg disposed within the tube and a leg disposed at an angle to the other leg and positioned alongside of the nozzle, and means for connecting each electrode to the tube in such a manner as to cause the end of the leg adjacent the nozzle

to be disposed out of the path of the jet 40 leaving the nozzle but sufficiently close thereto that the emitted spark can be blown into the jet by air forced through said tube.

3. In combination in an oil burner, a tubular member comprising an air tube, a fuel 45 nozzle in an end of said tube, parallel spark electrodes positioned in the tube each comprising an angularly bent rod including a substantially horizontal leg disposed within the tube and a slanting leg positioned 50 alongside of the nozzle and adjustable means for connecting each electrode to the tube in such a manner as to cause the end of the slanting leg of each electrode to be disposed out of the path of the jet leaving the 55 nozzle but sufficiently close thereto that the emitted spark can be forced into said jet.

4. The method of igniting a burner including a fuel nozzle which consists in supplying a jet of fuel from said nozzle, creating a spark producing difference in electrical potential between two points adjacent and sufficiently close to the jet so that the spark can be forced into the jet and forcing the spark into the jet leaving the nozzle. 65

5. The method of igniting a burner including a fuel nozzle which consists in supplying a jet of fuel from said nozzle, creating a spark producing difference in potential between two points adjacent and sufficiently 70 close to the jet so that the spark can be forced into the jet, circulating a charge of air past the nozzle for combustion purposes and utilizing said air to blow the spark into the jet leaving the nozzle. 75

In testimony whereof I have hereunto subscribed my name.

CHARLES L. RAYFIELD.
